Herbert McCornack.

UNITED STATES PATENT OFFICE

2,047,424

CENTRIFUGAL APPARATUS FOR CLEANING
AND CONDITIONING AIR

Herbert McCornack, Howey-in-the-Hills, Fla.

Application July 3, 1933, Serial No. 678,829

6 Claims. (Cl. 183—21)

My invention, which is a complement to my invention, Air washer and carburetors, under United States Patent No. 1,661,540, relates to improvements in that class of air cleaners and conditioners in which a liquid is used as a cleaning and conditioning agent and in which the air to be treated is introduced into a cylinder tangentially and sets up a whirling motion of the air as it contacts with the cleaning liquid.

10 Since cold liquid contacting with warm air causes the air to contract and eliminate moisture and, since warm liquid contacting with cold air causes the air to expand and absorb moisture and, since this apparatus functions to satisfy the affinity of air for liquid at all temperatures, the title Air cleaner and conditioner describes its inclusive application.

My Air washer and carburetor, under United States Patent No. 1,661,540, incorporates means 20 for returning the cleaning and conditioning liquid to the whirling air by causing the air to flow upward thru the cleaning and conditioning liquid in the catch-basin. My apparatus of the present application improves upon my original device by 25 the use of a plurality of restricted passages thru which the liquid is sucked up from the catch-basin in attenuated streams by the high velocity inflow of the tangential currents of air and is then discharged as finely atomized sprays of liquid into the whirling air in the cylinder.

The important object of my present invention is to increase the efficiency of the cleaning and conditioning process by bringing the cleaning liquid into more frequent and more intimate 35 contact with the air than in prior practice. Another essential object is to provide means, in certain applications of this device, for automatically ejecting from the apparatus the liquid and dirt which are removed from the air.

40 My invention will be understood from the following description, taken in connection with the accompanying drawing, in which,

Figure 1 is a cross-sectional elevation of an air cleaner and conditioner embodying my invention.

Figure 2 is a sectional plan on line 2—2 of Figure 1.

Figure 3 is a sectional elevation on line 3—3 of Figure 2.

50 Referring to the drawing, a cylinder 2 is shown in which the air is cleaned and conditioned, having a series of tangential inlets 4—4 thru which the air flows into the cylinder 2 and an exit 3 for the outflow of the air from the cylinder 2.

55 The cleaning liquid is held, by atmospheric pres-

sure, in reservoir 4 which has a conduit 5 leading from the reservoir 4 to catch basin 2x. A parabolic surface 7 of the liquid in the catch basin 2x, which is set up by the whirling action of the air in the cylinder 2, when the apparatus is in 5 operation, extends above the intake ends of the series of passages 6—6. These passages 6—6 extend upward to the discharge ends of the tangential air inlets 4—4. Cylinder 2 has a peripheral opening 8a thru which the whirling liquid 10 and dirt are ejected, against the resistance of vacuum in the cylinder, tangentially into conduit 8 and discharged thru trap 8z. 9 is a trap for the dirt and 10 is an outlet valve.

In the operation of this apparatus, liquid may 15 be used from any source but in the form of apparatus shown, water flows from reservoir 4 into catch basin 2x at the lower end of the cylinder 2 until the outlet of the conduit 5 is submerged, thereby shutting off the inflow of the atmosphere 20 to reservoir 4 and the corresponding outflow of the water. The air to be treated, as it flows thru tangential passages 4—4 into the cylinder 2, sucks up the liquid from the catch basin 2x in attenuated streams thru restricted passages 6 and discharges it in finely atomized jets tangentially 25 into the vortex of air and water in the cylinder. The liquid and dirt from the air is thrown outward and caused to rotate on the wall of the cylinder. The cleaned and conditioned air, at the 30 axis of the vortex, passes out thru exit 3 and the liquid which has not been absorbed by the air falls to catch basin 2x to again return thru another round of atomization.

To effectively accomplish this atomizing action, 35 it is important that the inlet ends of passages 6 be kept submerged practically all of the time. This is provided for in the relation of passages inlets 6 to the outlet of liquid conduit 5. As the liquid in the cylinder 2 is exhausted and the liquid surface in the catch basin 2x is lowered to a point where the outlet of conduit 5 is uncovered, air is let into reservoir 4 and a corresponding amount of water is released into catch basin 45 2x and by this means sufficient supply of water is maintained.

The greater frequency and intimacy of contact between the washing fluid and the air is accomplished by the provision in the apparatus of a plurality of restricted liquid passages arranged 50 so that they lead from points below the surface of the liquid in the catch basin to points at the discharge end of the tangential air inlets to the cylinder, in such way that the high velocity, incoming streams of air suck the liquid from the 55

5 basin in attenuated streams, finely atomize it and discharge it tangentially into the whirling air in the cylinder. The liquid, which is not absorbed by the air, is thrown by centrifugal force to the wall of the cylinder and falls to the catch basin to be returned repeatedly thru the atomizing process as above described.

10 Where, in some of the many uses to which this apparatus may be applied, it is desired to force the air, to be treated, thru the cylinder by super-atmospheric pressure, the water and dirt may be automatically ejected from the apparatus by the super-atmospheric pressure within the cylinder. In cases where the air to be treated is 15 drawn thru the apparatus by suction, and, when it is desired to constantly eject water and dirt from the apparatus, this is effected automatically against the resistance of the vacuum in the cylinder, by the momentum of the air and water as 20 they rotate on the wall of the cylinder, supplemented by the siphonic action of the ejected liquid, in the manner described. But where the use of this apparatus does not require the constant ejection of the water and dirt from the apparatus, pocket 9 and valve 10 are used to 25 discharge the accumulated dirt at the will of the operator.

I claim:

30 1. The method of centrifugally cleaning and conditioning air by causing washing liquid to be sucked thru restricted passages in attenuated streams from a liquid supply, outlets for said restricted passages being adjacent to inflowing 35 tangential streams of air where said liquid is expanded into atomized jets and delivered, tangentially, into a vortex of air which is in the process of being cleaned and conditioned.

40 2. In the art of cleaning and conditioning air, the method of sucking liquid in a multiplicity of attenuated streams and discharging said streams of liquid adjacent to inflowing tangential streams of air, where said liquid is expanded into atomized jets and delivering said liquid, tangentially, into 45 a whirling body of air which is in the process of being cleaned and conditioned and of causing the liquid, which has not been absorbed by the

air, to be repeatedly returned thru said whirling body of air in the process of atomization.

3. In a centrifugal apparatus for cleaning and conditioning air, a vertical or substantially vertical cylindrical chamber, means for introducing liquid into said chamber, tangential inlets for introducing air at high velocity into said chamber at its lower end and thereby causing the air and liquid to whirl, a receptacle at the lower end of said chamber to receive the returned, 10 unvaporized cleaning liquid from said whirling air and passages leading from below the surface of the liquid in said receptacle thru which the liquid is sucked in attenuated streams by said inflowing tangential streams of air and discharged in atomized sprays into the vortex of air and liquid, substantially as described.

4. In a centrifugal apparatus for cleaning and conditioning air, a vertical or substantially vertical cylindrical chamber, means for introducing liquid into said chamber, tangential inlets for introducing air at high velocity into said chamber at its lower end and thereby causing the air and water to whirl, a receptacle at the lower end of said chamber to receive the returned unvaporized cleaning liquid from said whirling air and means for sucking the returning liquid from the receptacle thru restricted passages in attenuated streams and discharging it in finely atomized jets tangentially into a vortex of air in the process of being cleaned and conditioned, substantially as described.

5. In a centrifugal apparatus for cleaning and conditioning air, as described in claim 4, a source of cleaning liquid supply, a conduit from said liquid supply source to said receptacle and means for controlling said supply, substantially as described.

6. In a centrifugal apparatus for cleaning and conditioning air as described in claim 4, suction means which draw the air to be cleaned through the apparatus, means for ejecting from the said apparatus the cleaning and conditioning liquid and the dirt, by the momentum of the whirling air and liquid in the cylinder, substantially as described.

HERBERT McCORNACK.
